UNITED STATES PATENT OFFICE.

WALTER PHILIP BRAENDER, OF MONTCLAIR, NEW JERSEY.

DESIGN FOR AN AUTOMOBILE TIRE.

Application filed January 31, 1921. Serial No. 441,488. Term of patent 3½ years.

To all whom it may concern:

Be it known that I, WALTER PHILIP BRAENDER, a citizen of the United States, residing at Montclair, in the county of Essex and State of New Jersey, have invented a new, original, and ornamental Design for Automobile Tires, of which the following is a specification, reference being had to the accompanying drawings, forming a part thereof, wherein—

I claim:

The ornamental design for an automobile tire, as shown.

WALTER PHILIP BRAENDER.
